(57) **CLAIM**

The ornamental design for an airway device, as shown and described.

DESCRIPTION

FIG. 1 is a side elevation view of an airway device showing the new design.

FIG. 2 is a front elevation view of an airway device showing the new design.

FIG. 3 is a rear elevation view of an airway device showing the new design.

FIG. 4 is a top view of an airway device showing the new design.

FIG. 5 is a cross-sectional view of an airway device taken in the direction of line 5-5 of FIG. 4 showing the new design; and,

FIG. 6 is a cross-sectional view of an airway device taken in the direction of line 6-6 of FIG. 1 showing the new design.

1 Claim, 6 Drawing Sheets

FIG. 1

FIG. 2

FIG. 3

FIG. 4

FIG. 5

FIG. 6
